UNITED STATES PATENT OFFICE

2,607,323

RECIPROCATING TYPE FLUID OPERABLE MOTOR

Andrew Kromhout, Elgin, Ill., assignor to Elgin Softener Corporation, Elgin, Ill., a corporation of Illinois

Application October 26, 1945, Serial No. 624,664

5 Claims. (Cl. 121—164)

1

This invention relates to a new and improved reciprocating type fluid operable motor, suitable for various uses, although herein disclosed as operatively connected with a chemical treatment pump apparatus.

The principal object of my invention is to provide in conjunction with the motor or prime mover, the uniform strokes of which are controlled by inlet and exhaust valves, a pressure fluid operated motor means of a reciprocating type for the instantaneous shifting of said inlet and exhaust valves in a predetermined timed relation to the operation of the pump-operating motor.

This invention is illustrated in the accompanying drawings, in which—

Fig. 1 is a side view of a chemical treatment pump apparatus in connection with which a reciprocating type motor of the kind to which my invention relates is shown;

Fig. 2 is a plan view of Fig. 1, with the right hand end portion broken away and shown in horizontal section;

Fig. 3 is a sectional detail of one end of the prime mover;

Fig. 4 is a section through one of the prime mover control valves, taken on the line 4—4 of Fig. 1;

Figs. 5 and 6 are flow diagrams of the prime mover;

Figs. 7 and 8 are two views of a modified or alternative valve construction, permitting the use of two valves in place of the four disclosed in Figs. 5 and 6;

Fig. 9 is a fragmentary view similar to Fig. 1, but showing the novel pressure fluid operated motor means of my invention for operating the control valves for the prime mover, and

Figs. 10 and 11 are sectional details on the correspondingly numbered lines of Fig. 9.

Similar reference numerals are applied to corresponding parts throughout the views.

In Fig. 1 only two treatment pumps 9 and 10 are shown, but it will soon be evident that a larger number of such pumps can be operated by the single prime mover 11 by plural connections to each of the cross-heads 12 and 13 in place of the single connections shown. While the prime mover 11 is herein disclosed as a water motor, it should be understood that my invention is not limited to the use of such a motor, inasmuch as any fluid under pressure, such as steam, oil, or air, may be used, whichever is most convenient for the particular installation.

The motor 11 comprises a cylinder 14 closed at

its opposite ends by plates 15 and 16 and having a piston 17 reciprocable therein. Piston rods 18 and 19 project through stuffing boxes 14a in the end plates, and there is a cushion spring 14b in each end of the cylinder to cushion the impact of the piston 17 on the end plates. The cross-heads 12 and 13, previously mentioned, are mounted on the outer ends of the piston rods 18 and 19 and are slidably mounted on guide rods 20 which are rigid with and extend from the opposite ends of the cylinder 14. Links 21 pivotally connected to the cross-heads 12 and 13 are pivotally connected to the upper ends of rocker arms 22 and 23, which are pivotally mounted at their lower ends on the base 24 that carries the pumps 9 and 10, as well as the motor 11. The rocker arms 22 and 23 are double, or bifurcated, as indicated in the top view, Fig. 2, so as to receive the links 21 between the halves thereof and also straddle the piston rods 25 and 26 of the pumps 9 and 10, respectively. It is obvious that if the cross-heads 12 and 13 were elongated transversely in relation to the piston rods 18 and 19, each or either of these cross-heads could be used for operating more than one pump by the provision of a plurality of link and rocker arm assemblies connected thereto, in which case more than one guide rod 20 would doubtless also be advisable for such cross-heads. The piston rods 25 and 26 extend through cylinder heads 27 on the cylinders 28 of the pumps 9 and 10 and each of these cylinders has a pipe connection 29 extending to a suitable container of treating chemical in liquid form (not shown), and another pipe connection 30 extending to the boiler (also not shown) that is to receive the chemical treatment, the connections 30 each containing a check valve (not shown) to permit flow of the chemical only toward the boiler. The piston rods 25 and 26 are longitudinally slotted from their outer ends, as indicated at 31, and are furthermore threaded substantially the full length of the slots, as indicated at 32, to receive manually adjustable nuts 33 and 34. Inside these nuts are H-shaped keys 35 which are slidable in the slots 31 and have stop portions 36 on the inner end arranged to form abutments for the cross-pins 37 that extend through the slots 31 and are slidable at their outer ends in short slots 38 provided in the rocker arms 22 and 23. Manifestly, since the rocker arms 22 and 23 are oscillated through a fixed angularity, the strokes given the piston rods 25 and 26 will be a maximum when the nuts 33 and 34 are adjusted inwardly as far as they can go, namely, to a point where the pins 37 have no lost

motion in the slots 31. However, the greater the amount of lost motion permitted by reason of a backing away adjustment of the nuts 33 and 34, the shorter the strokes of the piston rods 25 and 26, and obviously since the nuts 33 and 34 are independently adjustable, the discharge of either pump may be regulated as desired independently of the other, such adjustments being entirely feasible while the apparatus is in operation.

Mounted on top of the motor 11 are four valves A, B, C and D, each of which is a two-way cock type valve, as clearly appears in Fig. 4, each having an inlet 39 and an outlet 40. A tapered plug 41 is rotatable in a tapered seat 42 in the body of the valve and has an axial hole 43 extending therein from the small end to communicate with the radial port 44 that registers with the outlet port 40 in one position of the valve. The inlet 39 communicates directly with the chamber 45 at the large end of the plug 41 and also has communication through a passage 46 with a chamber 47 at the small end of the plug 41, thus giving balanced pressure on the plug and making it easy to turn. The plug has an operating stem 48 projecting therefrom, and there is a coiled compression spring 49 surrounding the stem in the chamber 45 which serves to keep the plug properly seated at all times, so as to minimize leakage. A crank 50 is provided on the outer end of each valve stem 48, and these cranks have a pivotal pin and slot connection with a valve throw-bar 51 that is reciprocable in guides 52 in a frame 53 on which the valves A-D are supported, the frame in turn being suitably supported on the motor 11. Two rollers 54 and 55 are carried on the throw-bar 51 in longitudinally spaced relation and are arranged to be engaged by a rocker arm 56 that is pivotally mounted intermediate its ends, as indicated at 57, on a cross-bar 58 on the frame 53. This rocker arm 56 forms a part of a load and fire mechanism, the same having a cage 59 carried on its upper end in which a roller weight 60 is carried and movable abruptly by gravity from one side of the rocker arm to the other when the rocker arm is moved slightly past a dead-center, whereby to actuate the throw-bar 51 abruptly from one limit position to the other and accordingly move the stems 48 of the valves A, B, C and D simultaneously through approximately 90° from one position to another. The rocker arm 56 is arranged to be moved toward and past dead-center from either of its extreme positions by rollers 61 and 62 which are adjustably mounted in longitudinally spaced relation on a rod 63 suitably supported at its opposite ends on the cross-heads 12 and 13, as indicated at 64, whereby to move to and fro with the piston rods 18 and 19 in the reciprocation of the piston 17 in the cylinder 14. The cylinder 14 has pipe connections 65 and 66 at its opposite ends, and these pipes are connected, as indicated at 67 and 68 in Figs. 5 and 6, to the valves A, B, C and D and to an inlet 69 and an outlet 70. The inlet 69 has communication with a suitable pressure fluid supply for continuous operation of the motor 11 throughout the operation of the boilers to which the chemical treatment is to be supplied from the pumps 9 and 10. The outlet 70 extends to a drain, or to a storage tank or sump, depending upon what use, if any, can be made of the discharging fluid.

The operation is as follows: Assuming that the parts are in the position shown in Fig. 1 and

fluid under pressure, such as steam, water, air, or oil, is delivered through the inlet 69 through valve A to the left hand end of the cylinder 14, as shown in Fig. 5, the fluid discharge from the right hand end of the cylinder 14 is conducted through valve C to the outlet 70, valves B and D during this phase of the operation being closed. The pump or pumps 9 accordingly have their piston rods 25 moved inwardly to discharge the chemical treatment fluid through the outlet connections 30 to the boilers, the amount discharged from each individual pump depending, of course, upon the adjustment of the nuts 33 on the piston rods of the individual pumps. In the same movement to the right, the pump or pumps 10 draw in chemical treatment fluid for discharge on the next stroke. If any increase or decrease is desired in the amount of chemical treatment fluid delivered to a certain boiler, it is a simple matter for the operator to adjust the nut 33 accordingly, and, as previously pointed out, such adjustment may be made while the apparatus is in operation. At a certain point in the movement to the right, the roller 61 engages the rocker arm 56 and starts movement thereof in a counter-clockwise direction toward a vertical dead-center position. At a certain point in this movement, namely, when the rocker arm 56 has been moved slightly past the dead-center position, the roller weight 60 rolls from the right hand end of the cage 59 to the left hand end, thus causing the rocker arm 56 to strike the roller 54 and move it and the throw-bar 51 abruptly to the left, which means that all of the valves A, B, C and D are suddenly shifted from the positions shown in Fig. 5 to the positions shown in Fig. 6. In this new position, the pressure fluid admitted at 69 is conducted through the valve D to the right hand end of the cylinder 14 so as to move the piston 17 to the left, the fluid in front of the piston being discharged from the cylinder through valve B to the outlet 70. The operation of the piston 17 to the left manifestly causes the discharging of the pump or pumps 10 and the charging of the pump or pumps 9, and here again the amount of discharge from the pump or pumps 10 obviously depends upon the adjustment of the nuts 34. The movement to the left continues until the roller 62 engages the rocker arm 56 and moves it toward and slightly past the dead-center position, whereupon the roller 60 returns to the right hand end of the cage 59 and throws the arm 56 abruptly in a clockwise direction to the position shown in Fig. 1. In this abrupt movement, the rocker arm 56 strikes the roller 55 and moves it and the throw-bar 51 to the right, shifting the valves A, B, C and D back to the positions shown in Fig. 5. Obviously, under certain conditions where one of a series of boilers is temporarily out of operation, the pump 9 or 10, as the case may be, supplying chemical treatment fluid, may be put out of operation temporarily without disturbing the operation of the other pump or pumps by merely backing up the nut 33 or 34, as the case may be, to an extent where the piston rod of the pump is not operated, and, of course, such adjustment may be made while the apparatus is in operation.

In passing, while I have shown four valves A, B, C and D, it should be clear that I may employ valves like that shown at E in Figs. 7 and 8, the plugs 41' of which have L-shaped ports 44' to conduct the incoming fluid from the inlet 39' to the cylinder 14, the connection for which is indicated at 71, as shown in Fig. 7, or

from the cylinder to the outlet 40', as indicated in Fig. 8, the plug 41' in this case being movable also through 90°, similarly as in the other valves A—D. With this construction, one valve takes the place of two of the other valves A—D, so that two are sufficient instead of four being required.

Referring now to Figs. 9 to 11, which disclose the improvements in the reciprocating type motor provided in accordance with my invention, I have disclosed two cylinders 72 and 73 that are suitably supported in fixed relation to the cylinder 14' of the motor 11', having pistons 74 therein connected to the opposite ends of a rod 75 on which an arm 76 is adjustably secured. This arm is adjustably secured to the throw-bar 51' that is reciprocable in guides 52 in a frame 53 on which the valves A—D are supported, the frame being in turn suitably supported on the motor 11'. The pistons 74 are arranged to be operated under fluid pressure, preferably using the same pressure fluid source as the motor 11', which may be steam, air, water, or oil, as mentioned above in regard to motor 11. Two three-way valves 77 and 78 suitably supported in fixed relation to the cylinders 72 and 73, respectively, have the rotary plugs thereof provided with operating arms 79 that are arranged to be operated by dogs 61' and 62' adjustably mounted on a rod 63' that is suitably supported at its opposite ends on the cross-heads 12' and 13', as indicated at 64', whereby to move to and fro with the piston rods 18' and 19' in the reciprocation of the piston in the cylinder 14'. The valves 77 and 78 are so arranged that when pressure fluid is admitted through valve 77 to cylinder 72, fluid may be exhausted from cylinder 73 through valve 78, and vice versa, as should be clear from inspection of Fig. 11.

The operation of the structure in Fig. 9 is the same as the structure of Fig. 1 insofar as the operation of the pumps by means of the motor 11' is concerned, and the individual adjustment of the pumps to regulate the amount of chemical treatment fluid discharged from each pump is concerned. Such adjustments may be made while the apparatus is in operation. At a certain point in the movement to the right, the dogs 61' engage the arms 79 and start movement thereof in a clockwise direction, whereby ultimately to shut off the flow of pressure fluid to the cylinder 72 and open it to the drain, and establish communication between cylinder 73 and the pressure fluid source. When that occurs, the throw-bar 51' is moved abruptly to the left by means of the arm 76 as the pistons 74 move to the left in the cylinders 72 and 73. In this new position, the pressure fluid admitted at 69, as shown in Fig. 6, is conducted through the valve D to the right hand end of the cylinder, in this case 14', so as to move the piston to the left, the fluid in front of the piston being discharged from the cylinder through valve B to the outlet 70. The operation of the piston in the cylinder 14' to the left causes the discharging of the pump or pumps 10 and the charging of the pump or pumps 9, referred to in Fig. 1, and this movement to the left continues until the dogs 62' have engaged and moved the arms 79 in a counterclockwise direction to an extent sufficient to restore the original system of communication, namely, where fluid under pressure is admitted to cylinder 72 and the cylinder 73 communicates with the drain. When that occurs, the pistons 74 are moved abruptly to the right,

thereby moving the arm 76 and the throw-bar 51' with it, shifting the valves A, B, C and D back to the positions shown in Fig. 5.

It is believed the foregoing description conveys a good understanding of the objects and advantages of my invention. The appended claims have been drawn to cover all legitimate modifications and adaptations.

I claim:

1. A reciprocating type motor comprising a cylinder, a piston reciprocable therein under pressure of fluid admitted to either end of said cylinder, a plurality of plug type valves for controlling the inlet and outlet of pressure fluid to and from said cylinder and comprising body members supported in fixed relation to said cylinder and plugs oscillatable in said body members, a throw-bar reciprocable relative to said cylinder and operatively connected with cranks on said plugs to oscillate the same together, and means for operating said throw-bar comprising a pair of cylinders in opposed relation having pistons reciprocable therein under fluid pressure, a rod interconnecting said pistons and having an operating connection intermediate its ends with said throw-bar, valves controlling the inlet and outlet of pressure fluid to and from said cylinders alternately, and means connected to and moving with the first named piston for operating said last named valves in a predetermined timed relation to the movement of the aforesaid piston, whereby to abruptly shift the throw-bar when the aforesaid piston nears the ends of its strokes.

2. A reciprocating type motor comprising a cylinder, a piston reciprocable therein under pressure of fluid admitted to either end of said cylinder, valve means for controlling the inlet and outlet of fluid to and from said cylinder, a throw-bar reciprocable relative to said cylinder and operatively associated with said valve means to shift the same, and means for operating said throw-bar comprising a pair of cylinders in opposed relation having pistons reciprocable therein under fluid pressure, a rod interconnecting said pistons and having an operating connection intermediate its ends with said throw-bar valves controlling the inlet and outlet of pressure fluid to and from said cylinders alternately, and means connected to and moving with the first named piston for operating said last named valves in a predetermined timed relation to the movement of the aforesaid piston, whereby to abruptly shift the throw-bar when the aforesaid piston nears the ends of its strokes.

3. A reciprocating type motor comprising a cylinder, a piston reciprocable therein under pressure of fluid admitted to either end of said cylinder, valve means for controlling the inlet and outlet of fluid to and from said cylinder, a throw-bar reciprocable relative to said cylinder and operatively associated with said valve means to shift the same, and means for operating said throw-bar comprising a pair of cylinders in opposed relation having pistons reciprocable therein under fluid pressure, a rod interconnecting said pistons and having an operating connection intermediate its ends with said throw-bar, two plug type valves for controlling the inlet and outlet of pressure fluid to and from said cylinders alternately and comprising body members supported in fixed relation to said first cylinder and plugs oscillatable in said body members, and a second throw-bar reciprocable relative to said first cylinder and operatively connected with cranks on said plugs to oscillate the same to-

gether in a predetermined timed relation to the movement of the first mentioned piston, whereby abruptly to shift the first throw-bar when the first mentioned piston nears the ends of its strokes.

4. In a valve operating mechanism for a reciprocating type motor, the combination of a throw-bar operatively associated with the valve means to be shifted, a pair of cylinders in opposed relation having pistons reciprocable therein under fluid pressure, a rod interconnecting said pistons and having an operating connection intermediate its ends with said throw-bar, valve means controlling the inlet and outlet of pressure fluid to and from said cylinders alternately, 10 and a second throw-bar reciprocable relative to said last mentioned valve means to operate the same in a predetermined timed relationship to the desired movement of the first throw-bar, so as to secure the abrupt shifting of the first mentioned valve means at predetermined intervals.

5. In a valve operating mechanism for a reciprocating type motor, the combination of a throw-bar operatively associated with the valve means to be shifted, a pair of cylinders in opposed relation having pistons reciprocable therein under fluid pressure, a rod interconnecting said pistons and having an operating connection intermediate its ends with said throw-bar, two 25 plug type valves for controlling the inlet and outlet of pressure fluid to and from said cylinders alternately and comprising body members

5 supported in fixed relation to said cylinders and plugs oscillatable in said body members, and a second throw-bar reciprocable relative to said last named valves and operatively connected with cranks on said plugs to oscillate the same together in a predetermined timed relation to the movement of the first throw-bar, whereby to secure the abrupt shifting of the first mentioned valve means at predetermined intervals.
